William A. Reid.

UNITED STATES PATENT OFFICE.

WITSEL R. DE CAMP, OF ROSELAND, NEW JERSEY, ASSIGNOR TO ADDOMETER CORPORATION, OF NEW YORK, N. Y., A CORPORATION OF DELAWARE.

SAFETY-LOCK FOR CALCULATOR RACK AND TYPE PLATES.

1,232,009.

Specification of Letters Patent.

Patented July 3, 1917.

Application filed October 29, 1915. Serial No. 58,587.

To all whom it may concern:

Be it known that I, WITSEL R. DE CAMP, a citizen of the United States, and resident of Roseland, in the county of Essex and State of New Jersey, have invented certain new and useful Improvements in Safety-Locks for Calculator Rack and Type Plates, of which the following is a specification.

This invention has for its object to provide an improved locking means for the rack bars in a calculator, that prevent undue or objectionable movement of the rack bars at the latter portion of an operation of the machine.

15 A further object of this invention is to provide yieldable means that will prevent disabling of such mechanism.

In the accompanying drawing illustrating one embodiment of my invention, Figure 1 shows it in side elevation. Fig. 2 is a similar view with the parts in different positions. Fig. 3 is a view taken at right angles to that of Fig. 1 showing the set of rack bars. Fig. 4 is a horizontal section through one of the 25 rack bars showing the abutment. Fig. 5 shows in elevation the stop plate, and Fig. 6 is an edge view of the same.

In the drawings are set forth a series of rack bars 7, that as shown have portions 8 for carrying type. The rack bars are vertically slidable on posts 9 supported in a frame, denoted generally by 10. It is customary in machines of this character to advance the rack bars in one direction by 35 springs, such as a coil spring 11, only one of which is shown in Fig. 3. And in such machines the movement in the opposite direction of all of the rack bars is generally effected by a single member such as a universal bar 12 that is caused to move up and down in the operation of the machine, permitting the springs to raise the rack bars, and which universal bar returns all of the rack bars to normal position at the proper 45 stage. Mechanism of this character is set forth in Letters Patent granted to J. C. Lotterhand, #1,102,157. In such patent is shown an operating member in the form of a bar or pitman 13 that moves back and 50 forth in the usual operation of the machine, by the handle or prime mover.

In machines such as set forth in said patent, the rack bars are permitted to rise during the advance of the pitman but such upward movement is not desired during the

return movement of the pitman. The purpose of the present mechanism is to lock the rack bars to prevent further advance during this return movement of the pitman; for the reason that at such stage the universal bar 12 is in elevated position, and under certain conditions the rack bars might be released by certain parts, such as the stop bars or numeral pinions, as set forth in said patent, and if the rack bars were not restrained they would move violently upward 60 to the limit of their movement.

As shown each of the rack bars 7 is provided with an abutment or lug 14 at its base that extends forwardly. These abutments 70 will be in alinement in the normal depressed position of the rack bars, and they are all engaged at a certain period by a single member, shown in the form of a cross bar 15. This bar is supported to move back and 75 forth, from the position in engagement with the abutments as indicated in Fig. 1, to a position free from the abutments, as shown in Fig. 2. In the former position the bar 15 will evidently prevent the rack bars from 80 being elevated by their springs, when otherwise free to move. The cross bar 15 is pivotally supported to swing between said positions, and is shown as having an arm 16 at one end that is pivoted at 17 on the side 85 plate 18; such pivotal means being preferably of a frictional character to retain the arm and bar in positions to which advanced by the moving means. At its other end the cross bar 15 is provided with an arm 19 90 pivoted at 20 to the side member 21, (see Fig. 3).

The pitman 13 is provided with a pair of stops that will engage the arm 16 at the final portion of its advance and return movement. And this means of engagement is preferably of a yieldable nature. As shown I provide a stop plate 22 that is pivoted at 23 on the pitman 13, the stop plate having an ear 24 that is normally pressed against 95 the edge of the pitman by spring 25 tensioned between the stop plate and the pitman. The stop plate is provided with lugs 26 and 27 that engage the arm 16 of the cross bar 15, preferably by a pin 28 thereon. 100

In the operation of the device, the cross bar 15 is normally retained free of the abutments 14, by reason of the lug 27 engaging the pin on arm 16, as indicated in Fig. 2. When the pitman 13 advances to the right 105

from the position of Fig. 2 to that of Fig. 1, the initial movement will free the arm 16, but this arm being frictionally held the cross bar 15 will not shift. At the final portion of this advance of the pitman the lug 26 will strike the pin on the arm 16 and swing the arm and bar 15 over to engage the abutments 14 on the rack bars 7, or to engage those that are in the normal depressed position, as indicated in Fig. 1. During the return of the pitman, the arm 16 and cross bar will remain in this shifted position until at the final portion of the return movement of the pitman the lug 27 of the stop plate 15 will strike the pin on arm 16 and shift the bar 15 away from position of engagement with the rack bars.

If when the bar 15 is being advanced to engage the abutments, any of the abutments that may lie in its path of movement and might thus interfere with the same, will not serve to disturb any of the parts, for the reason that the stop plate 22 can swing on the pitman 13 against the tension of its spring 25. But as soon as such obstruction is removed the cross bar will return to normal position.

Having thus described my invention, what I claim is:

- 30 1. In a calculator, the combination of a set of rack bars arranged to reciprocate, a cross bar movable to engage all of the rack bars to lock them in normal positions, the rack bars having abutment portions engaged by the cross bar, an operating member for the machine that is reciprocated in the normal operation of the machine, means for causing the operating member to shift the cross bar to engage and disengage the rack bars, and friction means connected with the cross bar for retaining it in the said engaging and disengaging positions to which moved by the operating member.
- 45 2. In a calculator, the combination of a set of rack bars arranged to reciprocate, a cross bar movable to engage all of the rack bars to lock them in normal positions, the rack bars having abutment portions engaged by the cross bar, an operating member for the machine that is reciprocated in the normal operation of the machine, means for causing the operating member to shift the cross bar to engage and disengage the rack bars, and a yieldable member connecting the operating member with the cross rod that can yield upon abnormal obstruction on said engagement of the operating member.

60 3. In a calculator, the combination of a series of rack bars arranged to reciprocate and provided with abutment portions, a cross bar pivotally mounted to swing to engage and disengage the rack bar abutments in normal position of the rack bars, a pitman adapted to be reciprocated, and a pair 65 of abutments on the pitman arranged to en-

gage the cross bar at the latter portion of its advance and return respectively whereby to shift the cross bar to engaging and disengaging positions with the rack bars.

4. In a calculator, the combination of a series of rack bars arranged to reciprocate and provided with abutment portions, a cross bar pivotally mounted to swing to engage and disengage the rack bar abutments in normal position of the rack bars, a pitman adapted to be reciprocated, and a pair of abutments on the pitman arranged to engage the cross bar at the latter portion of its advance and return respectively whereby to shift the cross bar to engaging and disengaging positions with the rack bars, 75 said abutments having a yieldable connection with the pitman to permit the yielding of the cross bar upon abnormal obstruction on said engagement of the operating member. 80

5. In a calculator, the combination of a series of rack bars arranged to reciprocate and provided with abutments, a cross bar movably supported to shift to and from position of engagement with said abutments 90 in the normal positions of the rack bars, a pitman adapted to be reciprocated in the normal operation of the machine, a stop plate pivoted on the pitman, and a spring normally holding the stop plate in a certain 95 position on the pitman, said stop plate having a pair of lugs arranged to engage the cross bar at the final portion of the advance and return of the pitman whereby to shift the cross bar to and from its said position 100 of engagement with the rack bars.

6. In a calculator, the combination of a series of rack bars arranged to reciprocate and provided with abutments, a cross bar movably supported to shift to and from position of engagement with said abutments in the normal positions of the rack bars, a pitman adapted to be reciprocated in the normal operation of the machine, a stop plate pivoted on the pitman, a spring normally holding the stop plate in a certain position on the pitman, said stop plate having a pair 110 of lugs arranged to engage the cross bar at the final portion of the advance and return of the pitman whereby to shift the cross bar to and from its said position of engagement with the rack bars, and friction means for retaining the cross bar in the positions to which shifted by the stop plate. 115

7. In a calculator, the combination of a set of rack bars arranged to reciprocate and provided with abutments, a cross bar having an arm at each end that are pivotally supported to permit the cross bar to swing to and from position of engagement with the 120 said abutments in the normal position of the rack bars, a pitman adapted to be reciprocated in the normal operation of the machine, a stop plate pivoted on the pitman and provided with an ear, a spring between 125

the pitman and the stop plate normally pressing the ear against the pitman, and a pair of lugs on the stop plate arranged to engage one of said arms alternately at the final portion of the advance and return of the pitman whereby to shift the cross bar to and from its said position of engagement.

8. In a calculator, the combination of a set of rack bars arranged to reciprocate and provided with abutments, a cross bar having an arm at each end that are pivotally supported to permit the cross bar to swing to and from position of engagement with the said abutments in the normal position of the rack bars, a pitman adapted to be recipro-

cated in the normal operation of the machine, a stop plate pivoted on the pitman and provided with an ear, a spring between the pitman and the stop plate normally pressing the ear against the pitman, a pair of lugs on the stop plate arranged to engage one of said arms alternately at the final portion of the advance and return of the pitman whereby to shift the cross bar to and from its said positions of engagement, and friction means on one of said pivoted arms to retain the cross bar in the positions to which shifted by the pitman.

WITSEL R. DE CAMP.
